DESIGN FOR A TOOTHPICK DISPENSER

Charles Koenig, Dayton, Ohio

Application January 24, 1947, Serial No. 136,365

Term of patent 7 years

(Cl. D52—1)

To all whom it may concern:

Be it known that I, Charles Koenig, a citizen of the United States, residing at Dayton, in the county of Montgomery and State of Ohio, have invented a new, original, and ornamental Design for a Tooth Pick Dispenser, of which the following is a specification, reference being had to the accompanying drawing, forming a part thereof.

In the drawing Figure 1 is a perspective view of a tooth pick dispenser, showing my new design; Figure 2 is a side elevation of the same; and Figure 3 is an end elevation of the same.

I claim:

The ornamental design for a tooth pick dispenser, as shown.

CHARLES KOENIG.
